UNITED STATES PATENT OFFICE.

JOHN H. BARR, OF NEW YORK, N. Y., ASSIGNOR TO REMINGTON TYPEWRITER COMPANY, OF ILION, NEW YORK, A CORPORATION OF NEW YORK.

TYPEWRITING MACHINE.

1,414,167.

Specification of Letters Patent. Patented Apr. 25, 1922.

Application filed September 1, 1920. Serial No. 407,303.

To all whom it may concern:

Be it known that I, JOHN H. BARR, a citizen of the United States, and resident of the borough of Manhattan, city of New York, 5 in the county of New York and State of New York, have invented certain new and useful Improvements in Typewriting Machines, of which the following is a specification.

My present invention relates to carriage 10 feeding or escapement mechanism for typewriting machines, and its object is to provide new and improved mechanism of the character specified. From another aspect the object of the invention is to provide novel 15 space bar mechanism, resulting in the elimination of "spreads," or the printing of a character in a place which should be a blank space.

To the above and other ends which will 20 hereinafter appear, my present invention consists in the features of construction, combinations of devices and arrangements of parts to be hereinafter described and particularly pointed out in the claims.

25 In the accompanying drawings which illustrate one form of my invention,

Figure 1 is a front to rear vertical sectional view of a typewriting machine embodying my invention, parts of the machine 30 being omitted and parts broken away.

Figure 2 is a fragmentary vertical sectional view corresponding to Fig. 1 but showing the parts in the position they occupy when the space bar or key is depressed.

35 Figure 3 is a vertical sectional view taken on the plane indicated by the dotted line $\alpha-\alpha$ in Fig. 1 and looking forward.

Figure 4 is a fragmentary perspective view of parts of the escapement mechanism.

40 Figure 5 is a rear elevation of the dog rocker and the escapement dogs or detents mounted on it.

As appears from Fig. 1, the main frame of 45 the machine comprises side plates or frames 1 which are connected at the front by a U-shaped frame 2 that encloses the keyboard, and at the rear by a cross plate or bar, not shown. Arranged for reciprocation above the main frame is a traveling carriage comprising an inclined plate or bar 3 at the ends 50 of which are secured forwardly extending side or end plates 4. The top and bottom of the plate 3 are formed with grooved ball seats or run ways 5 which receive sets of

anti-friction rollers 6. The upper set of 55 rollers 6 co-operate with a grooved ball seat formed in a guide bar 7 which extends cross-wise of the machine and is secured by screws 8 to the upper end portion of an angular bed plate or support 9 which is mounted on 60 the upper rear end portions of the frame plates 1 and is suitably secured thereto. The guide plate 7 is fixed to the top of the vertically disposed portion of the bed plate 9 and a forwardly extending horizontally disposed portion of said plate 9 terminates in a short upward extension 9^a having a 65 grooved run way or seat for the lower set of rollers 6. Pivottally mounted on the traveling carriage 3—4 is a roller platen 10 with 70 the front face whereof co-operate type bars 11. The set of type bars or printing devices are arranged in an arc of a circle below the platen and are normally horizontally disposed, their free ends resting on a pad 12 75 supported on a curved support or rest 13. Said type bars at their rear are pivoted on a common pivot wire 14 mounted on a vertical type bar support or segment 15. Each type bar is provided forward of its pivot with a 80 contact edge or face 16 for cooperation with the carriage feeding devices and said type bar is constantly connected to a printing key, to this end being formed below its pivot with an inclined cam slot 17. The slot 17 is en- 85 gaged by a headed pin 18 projecting laterally from the rear end of the longer arm of a bell crank 19, the series of bell cranks 19 being arranged in guide slots 20 formed at the rear of the support 13 and provided with 90 a common pivot wire 21. The shorter arm of each bell crank is connected by a link 22 with an angular lever 23 pivoted at 24 in a rectangular sub-frame 25 detachably mounted in the base or lower portion of the main 95 frame. Each angular lever 23 carries a headed pin 26 which engages in a slot 27 formed in the rear arm of a key lever 28, the set of key levers extending forward and being pivoted at 29 in the sub-frame 25. Each key 100 lever terminates at its forward end in an upright stem portion which is provided with a cap or key 30. It will be understood that when one of the printing keys 30 is depressed it will actuate its key lever 28, which through 105 the connected link 22 will swing the associate bell crank 19 on its pivot, causing the actuating pin 18 to operate the associate type

bar 11 which will be swung upward and rearward into printing contact with the platen 10 and the paper thereon.

During printing movements the type bars 5 will actuate the carriage feeding mechanism or escapement devices, which are connected with and control the carriage through a feed rack 31 which is mounted on the carriage and normally meshes with a feed pinion 32. 10 The escapement mechanism is of the direct or "ordinary" style, that is, it is adapted to afford a letter feed of the carriage during the return stroke of a printing key. The feed pinion 32 is operatively connected with 15 a toothed escapement wheel or circular rack 34 vertically disposed behind the rack 31 and under the carriage frame bar 3, the escapement wheel 34 and pinion 32 being mounted on a horizontal shaft 35 which extends fore and aft of the machine and has fixed bearings 36 and 37. Preferably sets of anti-friction balls (not shown) are interposed between the ends of the shaft 35 and the fixed bearings 36 and 37. Co-operative 20 with the teeth of the escapement wheel 34 are escapement dogs or detents 38 and 39, these dogs being mounted on a dog carrier or rocker designated as a whole by the numeral 40 and comprising an upright plate- 25 like portion 41 and a cylindrical cross portion 42, the latter formed at its ends with seats or depressions which receive the pointed ends of bearing pins 43 mounted on a stationary bracket or bearing member 44. 30 The dog 38 is a feed or stepping dog being pivoted at 45 at the rear face of the dog rocker and the tail of said dog has connected to it a coiled spring 46, one end of said spring being anchored to a screw pin 47 projecting 35 from the part 41 of the dog rocker. The spring 46 tends constantly to turn the upper or toothed end of the dog 38 towards the right, as viewed from the rear, but this tendency is opposed normally by the carriage 40 motor or main spring (not shown) of the machine, which main spring is connected to the carriage so as constantly to urge it in printing direction. The pull of the spring drum or main spring is transmitted 45 through the carriage rack 31 to the feed pinion 32 and thence to the escapement wheel 34 which as a result has a constant tendency to turn so that the teeth at its lower side will move leftward, as viewed from the 50 rear of the machine. Considering Fig. 5, it will be seen that this leftward movement of the escapement wheel teeth is in opposition to the pull or action of the restoring spring 46 of the feed dog 38. 55 The feed dog 38 is normally engaged with the escapement wheel 34, as shown in Figs. 1 and 5, the engaged tooth of the escapement wheel maintaining said dog 38 in contact with a limiting stop 48 projecting from the 60 dog rocker into the path of the dog 38.

When freed from the escapement wheel the dog 38 will be swung rightward from the Fig. 5 position by the action of the spring 46, this rightward movement of the dog about its pivot 45 being limited by a stop 70 49 projecting from the dog rocker. When the dog 38 is released as described, which results from the rearward swinging movement of the dog rocker as hereinafter explained, the fixed or holding dog 39, which is an upward projection of the rocker plate 41, will be swung into the path of the escapement wheel, the beveled rear face of the dog 39 engaging with the escapement wheel tooth which has just been cleared by the feed or 80 pivoted dog 38. The dog 38 having been swung by its spring 46 far enough rightward to clear the escapement wheel tooth with which it had previously engaged, will on the return movement of the dog rocker 85 be brought into the path of the oncoming escapement wheel tooth and will be carried by said tooth back into engagement with the stop 48, thus resulting in a leftward feed or advance movement of the carriage 90 for a letter space distance, this movement taking place on the return movement of the dog rocker and of the operated printing key 30. The escapement in other words, is what is known in the art as "ordinary" or direct, 95 in contra-distinction from a "reverse" or full drop escapement whose use results in the letter feed taking place during the key depression or before the return movement of the key begins. Movement from the printing keys to the dog rocker is transmitted through the type bars whose contact faces 100 16 are adapted to co-operate with the front edge of a universal bar 50, said universal bar being arcuate in shape and being housed in 105 a seat or depression 51 in the rear of the type bar segment 15. Near its ends the universal bar 50 has rearward extensions 52 which are pivotally connected at 53 with crank arms 54 fixed to a shaft 55 from which 110 said crank arms 54 project upwardly. Centrally the shaft 55 has a rearwardly extending crank arm 56. The lower middle portion of the universal bar 50 is provided with a rearwardly extending arm 57 carrying a 115 contact device or upturned rear end portion 58 which is adapted to engage with the point of the adjustable contact pin or screw 47 which projects forward from the dog rocker. The arm 57 has a downwardly extending lug 60 formed with an open-mouthed slot 61 that is engaged by a pin 62 projecting laterally from the upper free end of a crank arm 63 fixed to a pivotal axis 64 which also carries a rearwardly extending 120 crank arm 65, the crank arm 65 being connected to the crank arm 56 by a vertical link 66. This link 66, together with the crank arms 56 and 65 and the crank arms 54 and 63, synchronizes the movements of the uni- 125 130

versal bar frame comprising the curved universal bar 50 and its rearward extension 57. This frame is supported from the axes 55 and 64, these axes being so mounted that they participate in any case shifting movements to which the type bar segment 15 may be subjected, the result being that the universal bar at its front edge is always in position normally to receive actuations from the contact devices or edges 16 of the type bars. The universal bar frame is provided with a coiled restoring spring 67 which is horizontally disposed and at its rear end is hooked over a pin 68 projecting upward from the arm 57. The forward end of said spring is fixed to an adjustable anchorage 69 mounted on a pin or screw 70 supported on an arm 71 fixedly connected to and extending downward behind the type bar segment 15. The universal bar construction and mounting need not be further described since no claim is made for them in the present case. The spring 67 normally maintains the universal bar in contact with the front wall of the depression 51 and at this time the contact or screw 47 on the dog rocker is contiguous to the end portion or contact piece 58 of the universal bar, the dog rocker being maintained in this position normally by the usual dog rocker spring 72. When one of the printing keys 30 is depressed it acts through the train of type bar actuating devices to swing the connected type bar up to printing contact with the platen and causes the contact face 16 of said type bar, acting against the universal bar, to move the universal bar rearward against the pull of the spring 67, this movement being transmitted through the screw 47 to the dog rocker 40, which will be swung rearward from the Fig. 1 position, releasing the feed or loose dog 38 from the escapement wheel and bringing the fixed dog 39 into engagement therewith. The feed dog 38 when released will be swung sidewise on its pivot 45 into position to engage with the next tooth of the escapement wheel when the latter starts to turn, during the return stroke of the operated printing key 30. During said return stroke the actuated type bar will swing back, permitting the universal bar to be restored by its spring 67 and the dog rocker to be restored by its spring 72, the dog rocker as it swings back to normal carrying the dog 39 out of the escapement wheel and bringing the stepping dog 38 into the path of the oncoming tooth, thus permitting a letter space advance movement of the carriage under the impulse of the carriage spring, as has been already explained.

Referring now specifically to the novel features of my present invention, these comprise primarily means for preventing what is known as a "spread" or the striking of the first character of a word at the point or

place on the paper which should be a space. The escapement mechanism as has been explained is what is called a direct or sometimes a "no drop" escapement; that is, it is an escapement which under the actuation of the printing keys affords no movements of the carriage on down strokes of the keys but results in substantially full letter space step by step movements on the return or up-strokes of the printing keys. The space bar mechanism heretofore associated with escapement mechanism of the kind described and affording "ordinary" or direct feed is inherently slow, because of the fact that operators are not so speedy with the thumb as with the fingers, the thumb usually being employed to actuate the space bar; and consequently, as well for the further reason that there is a common tendency on the part of operators to dwell on the space bar, liability to produce "spreads" is quite prevalent. This result of preventing "spreads" is accomplished in the present instance by providing a space key or bar mechanism in which a full letter space movement of the carriage results from the depression only of the space bar, such letter space movement not requiring as heretofore the return of the space bar towards normal position to bring it about. By this means "spreads" are prevented since even if the operator should dwell on the space bar or key at the bottom of its stroke, the spacing of the carriage will nevertheless have been accomplished, so that if the operator should actuate one of the printing keys, resulting in the printing of a character, this character will be impressed on the paper following a blank space thereon. The space key or bar in the present instance is in the form of a cross bar 73 extending from side to side of the machine forward of the letter keys and connecting the front ends of two space bar levers 74, which at their rear ends are fixedly secured to a rock shaft 75 bearing in brackets or supports 76 fixed to and extending downward from the subframe 25, the devices aforesaid constituting a spacing frame. Arranged at the middle of the rock shaft 75 and extending rearward therefrom is a curved lever arm 77. At its front end this lever arm is bent around the rock shaft 75 to which it is secured by a cross pin 78. The rear or free end of the crank arm 77 is adapted to contact with the curved under face 79 of an angular lever or cam member 80, which is pivoted at 81 to an angular bracket 82, this bracket having an ear 83 bent from it at right angles and formed with elongated slots 84, Figs. 3 and 4. These slots provide for adjustment of the bracket along the rear face of the sub-frame 25 to which said bracket is secured by headed screws 85 passing through the slots 84 and threaded into the sub-frame 130

25. The upstanding arm of the cam plate or member 80 is provided near its end with a laterally projecting pin 86 which engages in a slot 87 formed in the shorter arm 88 of a lever member or so-called hammer or striker which further comprises an angularly disposed arm 89 terminating in an enlargement or head 90. The lever or hammer is further provided with an upwardly extending toe piece or contact 91 projecting upward above its pivot. This pivot is a headed shoulder screw 92 which is threaded into the upper end of the bracket 82, a washer 93 being interposed between the hammer and the bracket so as to bring the plane of the hammer to the right of the plane of cam member 80 and permit their pin and slot connection. The contact or toe 91 is adapted to co-operate with the lower 10 free end of an arm 94 which is fixed to the front of the dog rocker above its pivot and curves forward and downward therefrom. The arm 94 has at its upper end an angularly disposed ear 95 which receives screws 15 96 that secure it to the front face of the rocker plate 41. The space bar, it will be noted, is disconnectably connected with the dog rocker. Normally the cam member and the connected hammer device are related as 20 in Fig. 1, the forward portion of the contact face 79 being contiguous to the space bar lever arm 77, the pin 86 being engaged with the lower end of the slot 87 and the toe 91 of the hammer being separated from the 25 lower free end of the arm 94. Suppose a downward stroke is given to the space bar 73 fully to actuate it, the limit of such actuation being determined by the stop 73^a lying in its path. This space bar stroke will be 30 transmitted by the arm 77 through its rolling contact with the member or lever 80 and through the pin and slot connection 86, 87 to the hammer member causing it through its toe piece 91 to over-travel sufficiently to 35 give a hammer blow to the arm 94 effective to actuate the dog rocker, swinging the dog rocker from the Fig. 1 to the Fig. 2 position so that when the dog rocker completes its 40 vibratory movement and swings back to 45 normal, which it will do as the hammer device rebounds or swings back, a letter space feed movement of the carriage will take place irrespective of whether the space bar is released from its depressed position or 50 not, and under a quick action causes the carriage to space a letter feed distance before the space key stroke is completed, giving a full drop or reverse feed. This results 55 from the fact that the mechanism is so set 60 that the hammer will operate the escapement only by overthrow on the down stroke of the space bar; that is, a slow depression of the space bar resulting in a slow turning of the hammer device about its pivot 65 92, while it will carry the nose or toe 91

into engagement with the arm 94 and will actuate the dog rocker to some extent, will not swing said dog rocker far enough rearward to disengage the feed dog 38 from the escapement wheel 34. The usual operating 70 stroke is necessary to this end, such stroke causing overthrow as described, so that the inertia of the dog rocker will cause the dogs and escapement wheel to co-operate effectively. It will be understood that the actuation of the escapement mechanism by the space bar 73, as has just been described, will not affect the printing key operated universal bar, but that during such operation the contact 59 will swing away from the contact 58, which latter will remain motionless. Furthermore, it will be apparent that when the escapement mechanism is operated by the universal bar, the space bar and hammer mechanism will not be affected, but the dog 80 rocker will swing on its pivot, carrying with it the arm 94 without affecting the toe piece 91 or any other part of the mechanism connected with the space bar.

Certain novel features disclosed in the drawing are not claimed herein since they do not in themselves constitute part of the present invention.

Various changes may be made without departing from my invention.

What I claim as new and desire to secure by Letters Patent, is:

1. In a typewriting machine, the combination of a traveling carriage, carriage feeding devices comprising a pivoted dog rocker, a pivoted hammer device, and a key effective on said hammer device to cause it to actuate said dog rocker through striking a blow.

2. In a typewriting machine, the combination of a traveling carriage, carriage feeding devices comprising a pivoted dog rocker, a pivoted hammer device normally separated from said dog rocker, and a key effective on said hammer device to cause it to actuate said dog rocker resulting in a vibratory movement of said dog rocker due to the overthrow of said hammer device.

3. In a typewriting machine, the combination of a traveling carriage, carriage feeding devices comprising a pivoted dog rocker, an arm fixed thereto, a pivoted hammer device having a projection co-operating with said arm, a key and connections to said hammer device for communicating a hammer blow to said arm and operating said dog rocker through overthrow of said hammer device.

4. In a typewriting machine, the combination of a carriage, carriage feeding devices comprising a dog rocker, a key operated universal bar for actuating said dog rocker, and key operated devices for giving a hammer blow to said dog rocker and effectively actuating said dog rocker through overthrow of certain of said key operated devices.

5. In a typewriting machine, the combination of a carriage, carriage feeding mechanism comprising a dog carrier, a universal bar for actuating said dog carrier, printing keys operative on said universal bar, devices for giving a hammer blow to said dog carrier, and a space key effective on said last named devices to cause overthrow of certain of said devices. 5
- 10 6. In a typewriting machine, the combination of a carriage, carriage feeding devices comprising a dog carrier, a universal bar for actuating said dog carrier, printing keys operative on said universal bar, and a space key 60 independent of said universal bar and effective to actuate said dog rocker, full operative movement of said dog rocker in one direction being due to the inertia of said dog rocker. 15
- 20 7. In a typewriting machine, the combination of a traveling carriage, carriage feeding devices comprising a pivoted dog rocker, an arm fixed thereto, a pivoted hammer device having a projection co-operative with 70 said arm but normally separated therefrom, a space bar frame, and a member interposed between said hammer device and said space bar frame, said member having rolling contact with said space bar frame and a pin and 75 slot connection with said hammer device. 25
- 30 8. In a typewriting machine, the combination of a traveling carriage, carriage feeding devices comprising a pivoted dog rocker, a pivoted hammer device effective on said 80 rocker, a pivoted cam member having a pin and slot connection with said hammer device, and a space bar or key effective on said cam member. 35
- 40 9. In a typewriting machine, the combination of a traveling carriage, carriage feeding devices comprising a pivoted dog rocker, a pivoted hammer device effective on said 85 rocker, a pivoted cam member having a pin and slot connection with said hammer device, and a key operated arm having a 90 rolling contact with said cam member. 45
- 50 10. In a typewriting machine, the combination of a traveling carriage, carriage feeding devices comprising a pivoted dog rocker, a space bar, a pivoted arm operative thereby, an angular lever having a rolling contact 100 with said arm, a hammer member with which said lever has a pin and slot connection, and an arm rigid with said dog rocker and operative by a contact on said hammer member. 55
- 55 11. In a typewriting machine, the combination of a carriage, escapement devices comprising a pivoted dog rocker, printing keys operative on said escapement devices, 105 a space bar, a cam plate operative by said space bar, and a hammer device operative by said cam plate and effective to vibrate said dog rocker. 60
12. In a typewriting machine, the combination of a carriage, escapement devices 65 comprising a pivoted dog rocker, printing keys operative on said escapement devices, a space bar, a pivoted cam having a curved face, an arm operative by said space bar and effective on said curved face, and a 70 hammer operative by said cam to vibrate said dog rocker to cause a feed of the carriage. 75
13. In a typewriting machine, the combination of a carriage, escapement devices 80 comprising a pivoted dog rocker, printing key levers, a space bar, a detachable sub-frame on which said key levers are mounted, a bracket on said sub-frame, a cam plate pivoted on said bracket, and a hammer device pivoted on said bracket and operative by said pivoted cam-plate, said hammer device being effective to cause a vibration 85 of said dog rocker and a feeding movement of the carriage. 85
14. In a typewriting machine, the combination of a carriage, escapement devices comprising a pivoted dog rocker, printing keys effective on said dog rocker to cause a direct or "ordinary" feed of the carriage, a 90 space bar, a pivoted arm operative thereby, a pivoted cam plate having a rolling contact with said arm, and a pivoted hammer device having a pin and slot connection with said cam plate and provided with a contact normally separated from said dog rocker but effective to vibrate the same. 95
15. In a typewriting machine, the combination of a platen, a carriage, an escapement wheel, a dog rocker, escapement dogs thereon, a universal bar operative on said dog rocker, type bars, printing keys constantly connected to said type bars and effective to cause said type bars both to print against the platen and also to actuate the universal bar, 100 and a space bar effective to cause an operation of the dog rocker, full operative movement of said rocker in one direction being due to the inertia of the dog rocker itself. 105
- Signed at the borough of Manhattan, city 110 of New York, in the county of New York and State of New York, this 27th day of August, A. D. 1920.
